BLOOD TELLTALE SYRINGE

Morris Dann, Havertown, and John J. Peterson, Philadelphia, Pa., assignors to American Home Products Corporation, New York, N. Y., a corporation of Delaware

Application November 30, 1955, Serial No. 550,016

5 Claims. (Cl. 128—218)

This invention relates to a blood telltale syringe cartridge. More particularly it relates to an injection syringe cartridge comprising an ampule containing an injectable drug, having a movable plunger at its proximal end, and being closed at its distal end by a perforated stopper in which is mounted a hollow injection needle, the inner or proximal end of the needle being bent towards the inner wall of the ampule and terminating adjacent thereto. The invention includes the complete syringe as well as the ampule-needle assembly, here designated as the cartridge.

In using an injection syringe it is common practice, after inserting the needle, to aspirate a small amount of tissue fluid to determine whether or not the needle has penetrated a blood vessel. If it has, a droplet of blood is drawn into the ampule. This droplet must be immediately visible if the determination is to be useful.

The visibility of the aspirated blood droplet offers no particular problem if the injected material is a transparent and non-viscous liquid, but if it is opaque and viscous, the aspirated droplet is often completely invisible. Many of the currently used antibiotic preparations are viscous and opaque and consequently pose the problem of visibility of aspirated blood not solved by the syringes commonly in use.

One solution of this problem is suggested in the Lockhart Patent No. 2,693,183, November 2, 1954. According to this patent, in the neck of the ampule a plug is provided having a chamber opening adjacent the ampule wall; the chamber communicates distally with the injection needle and proximally with the interior of the ampule. Aspirated blood fills this chamber and thus becomes visible through the ampule wall. While this arrangement overcomes the disadvantages of the commonly used syringes when injecting opaque viscous materials, it requires an unusually large stopper of special form, and enough blood must be aspirated to fill the chamber in order to become visible.

It is one object of our invention to provide a simplified means of making aspirated blood visible in an injection syringe when used with opaque viscous materials.

It is a further object of our invention to provide means for making visible an extremely small droplet of aspirated blood.

It is an additional object of our invention to provide a syringe from which aspirated blood may be completely expelled, thus permitting a further trial insertion.

Other objects and advantages of our invention will be apparent to those skilled in the art from the following disclosure.

According to our invention we provide an injection needle mounted in the distal end of an ampule and communicating with its interior, the proximal end of the needle being bent towards the wall of the ampule and terminating adjacent to it or even touching it. The angle of bend is not critical, but a 60° bend has been found satisfactory. The proximal end of the needle is preferably cut off square so that the plane defined by the end

2

makes an approximately 30° angle with the wall of the ampule, thus permitting a small droplet of blood to be held between the needle end and ampule wall and to be visible through the wall. Since the bend in the needle is not visible to the user, we find it desirable, though not necessary, to orient the bend so that it points in the direction of the bevel at the distal end of the needle. This permits the user, by observing the bevel, to insert the needle in such a way that the aspirated blood will appear at a convenient point for observation. The small droplet of aspirated blood may be completely expelled from the needle, thus permitting an additional trial insertion. This appears impractical in syringes in which a relatively large chamber is filled with the aspirated blood.

If the cartridge of our invention is used in a permanent syringe body, e. g. in a metal syringe, it is desirable that the usual windows in the sides of the syringe body be extended distally and that additional small windows be provided at the distal end between the larger windows in order that the transparent wall of the ampule may be visible for most of its circumference close to the hub ferrule.

The needle of our invention is preferably secured to the ampule by means of a hub having a skirt crimped around the flanged neck of the ampule, the hub being thereby held firmly against the rubber stopper. Alternatively a separate ferrule may be used instead of the skirt integral with the hub. This method of securing a needle to an ampule is illustrated in Dann Patent 2,671,450, March 4, 1954, Figs. 2, 4 and 5.

Particular embodiments of our invention are described below and shown in the accompanying drawings, but these are intended to be illustrative only and not to limit our invention the scope of which is defined in the appended claims.

In the drawings:

Fig. 1 represents in longitudinal section a preferred embodiment of a syringe cartridge embodying our invention;

Fig. 2 is an enlarged section of the distal end of the cartridge of Fig. 1;

Fig. 3 is a view of the cartridge of Fig. 1 mounted in a cylindrical syringe body;

Fig. 4 is a longitudinal section of our invention incorporated in a disposable or so-called "one shot" syringe;

Fig. 5 is a longitudinal section of a modified form of cartridge incorporating our invention; and

Fig. 6 illustrates a modified form of needle hub.

In the preferred embodiment of our invention, an ampule 1 is provided at its proximal end with a slidable plunger 2 having a threaded connection 3 adapted to engage a syringe plunger rod 4; this permits retraction of the plunger for aspiration.

The distal end of the ampule is drawn out to a narrow neck 5 having a flanged mouth 6. This mouth is closed by a perforated stopper 7 in the perforation of which is mounted injection needle 8 communicating with the interior of ampule 1 and the injectable drug 9 contained therein. The proximal end of the stopper may be cut away as at 71 (Fig. 5) to form a recess for the bent end of the needle and prevent contact of the plunger with the needle.

Needle 8 is fixedly secured in metal hub 10 which has an integral skirt 11 crimped around flanged mouth 6, holding the hub tightly against stopper 7 to form a liquid- and bacteria-tight joint. Instead of integral skirt 11, the hub may have the form 12 provided with a separate ferrule 13 which functions in the same way as skirt 11. Thus hub is shown in Fig. 6. The hub 10 is advantageously provided with a male thread 14 to engage a mating

female thread in syringe body 15 (Fig. 3) or tubular cover 16 (Fig. 4) but this is not essential.

The proximal end of needle 8 is bent at 17 for a sufficient length to bring the proximal tip of the needle close to or in contact with the inner wall of neck 5, thereby permitting a small droplet of aspirated blood 18 to be held by surface tension between the wall of the ampule and the end of the needle and thus to be visible to the user of the syringe. The bend is made so as not to reduce the lumen of the needle substantially and the angle of bend is preferably about 60°, the end of the needle being cut square so as to form an angle of about 30° with the wall of the ampule. The bend is advantageously made in the direction of the bevel at the distal end of the syringe so that the orientation of the bend may be observed by the user as explained above.

The cartridge is adapted to be used in a syringe body 19 which is a modification of the conventional syringe body as shown in Fig. 3. The modification consists in extending slots 20 at the distal end 21 and providing additional windows 22 to permit viewing of the droplet of aspirated blood.

A modified cartridge of this type is also adapted for use in a disposable or "one shot" syringe of the kind disclosed and claimed in Dann Patent No. 2,671,449, March 9, 1954. One embodiment of such use is illustrated in Fig. 4. In this case the ampule 23 is provided with a flange 24 at its proximal end to act as a seat for a rubber finger piece 25. The needle is protected by a rubber sheath 26 and a tubular cover 27 which also serves as a push rod when screwed onto threaded connection 3 as disclosed in the last cited Dann patent.

Our invention is also applicable in a further modification of the cartridge as illustrated in Fig. 5. Here ampule 28 is a simple glass cylinder closed at its proximal end by the usual plunger 2 and at its distal end by perforated flanged stopper 29. Needle 30 in this case is similar to needle 8 but lacks hub 10. Instead a flange 31 is affixed to the needle to take the thrust of insertion.

We claim:

1. In an injection syringe cartridge comprising a transparent ampule adapted to contain an injectable drug, closed at its proximal end by a slidable plunger having a threaded connection for the push rod of a syringe and closed at its distal end by a fixed perforated stopper hav-

ing a hollow injection needle fixed in its perforation and communicating at its proximal end with the interior of the ampule, said cartridge being adapted for both injection and aspiration, the improvement which comprises: an injection needle in the recited combination bent near its proximal end for a sufficient length and through a sufficient angle to bring its proximal end adjacent the wall of the ampule, whereby blood aspirated through the needle makes contact with the wall of the ampule and becomes visible therethrough.

2. The improvement defined in claim 1 in which the ampule has a narrow flanged mouth at its distal end, the injection needle is fixedly mounted in a hub, and the hub is secured against the fixed stopper by a member crimped around the flange of the ampule.

3. The improvement defined in claim 1 in which the needle is beveled at its distal end and the bend in the needle is approximately 60° and in the direction of the bevel at the distal end.

4. An injection syringe comprising a tubular body adapted to receive an injection cartridge and having a push rod at its proximal end adapted to be positively engaged with the cartridge plunger, an injection cartridge as defined in claim 1 within the tubular body, and in the wall of the tubular body a plurality of inspection openings spaced around the circumference of the body and extending toward its distal end beyond the proximal end of the injection needle.

5. A disposable injection syringe comprising a cartridge as defined in claim 2, the ampule of said cartridge being provided at its proximal end with a finger piece, and a tubular needle cover adapted at one end to fit firmly and removably over the needle hub and at its other end to positively engage the slidable plunger in the ampule, whereby the needle cover serves as a push rod, permitting aspiration prior to injection.
